(57) **CLAIM**

I claim the ornamental design for a carbine pistol buffer tube, as shown and described.

DESCRIPTION

FIG. 1 is a front view of the carbine pistol buffer tube showing my new design;

FIG. 2 is a top-front perspective view thereof;

FIG. 3 is a left side view thereof, the right side being a mirror image;

FIG. 4 is a top view thereof;

FIG. 5 is a bottom view thereof;

FIG. 6 is a rear view thereof; and,

FIG. 7 is a bottom-rear perspective view thereof.

The broken lines in the drawings depict unclaimed portions of the buffer tube only and form no part of the claimed design.
